HIGH BACK EASY CHAIR

Leo Jiranek, Old Greenwich, Conn., assignor to Heywood-Wakefield Company, Gardner, Mass., a corporation of Massachusetts

Application September 10, 1956, Serial No. 42,891

Term of patent 7 years

(Cl. D15—1)

FIG. 3.

FIG. 4.

FIG. 5.

Fig. 1 is a front perspective view of a high back easy chair showing my new design;

Fig. 2 is a rear perspective view thereof on a scale somewhat reduced with respect to the scale of Fig. 1;

Fig. 3 is an enlarged detail fragmentary view on the line 3-3 of Fig. 1;

Fig. 4 is a fragmentary view on the line 4-4 of Fig. 3; and

Fig. 5 is a perspective view of one of the arm rests, substantially on the scale of Figs. 3 and 4.

I claim:

The ornamental design for a high back easy chair, substantially as shown.
